BATH ENCLOSURE DOORS

Joseph Mango, Midlothian, Ill., assignor to Beuti-Dor,
Inc., Chicago, Ill., a corporation of Illinois

Filed Apr. 23, 1969, Ser. No. 16,870

Term of patent 14 years

Int. Cl. D23—02

U.S. Cl. D23—69

I claim:

The ornamental design for bath enclosure doors, as shown.
